UNITED STATES PATENT OFFICE.

STEFAN ZOCH, OF MUNISING, MICHIGAN.

BABY-WALKER.

1,350,401.

Specification of Letters Patent. Patented Aug. 24, 1920.

Application filed March 22, 1919. Serial No. 284,235.

To all whom it may concern:

Be it known that I, STEFAN ZOCH, a citizen of Poland, residing at Munising, county of Alger, and State of Michigan, have invented certain new and useful Improvements in Baby-Walkers, of which the following is a specification.

This invention relates to improvements in devices for teaching children the natural use of their lower limbs, and the principal object is to provide an apparatus in which an infant may be placed either in a standing or sitting posture, according to their age and ability, the apparatus being movable in the manner of a baby coach or carriage, either by an attendant or by the infant itself, whose body will be supported free from accidents likely to occur to creeping children.

20 A further object is to provide means whereby the infant may be seated and fed if desired, certain parts of the apparatus acting as a table and others as a seat.

25 And finally, to provide means whereby the flooring or seat element may be held when in a raised position in a safe manner.

These and other like objects are attained by the novel construction and combination of parts hereinafter described, and shown 30 in the accompanying drawings forming a material part of this disclosure, and in which:

Figure 1 is a top plan view showing a baby carriage made in accordance with the 35 invention.

Fig. 2 is a horizontal sectional view taken on line 2—2 of Fig. 3.

Fig. 3 is a vertical sectional view taken substantially through the center of the apparatus.

40 Fig. 4 is a top plan view showing in detail the construction used in holding the hinged elements when in a raised position.

Fig. 5 is a side elevational sectional view 45 of the same, and

Fig. 6 is a side elevational view of the complete apparatus.

The device comprises a rectangular plate 10, having notched corners 11, receptive of the wheels 12, arranged in pairs and journaled upon axles 14, which extend across

and below the plate 10, forming a species of truck.

Vertical posts 15 are secured over the axles at the corners of the platform 10, 55 these posts extending up to a top plate 16, containing a relatively large central opening 18, and provided with a raised marginal rim 17 acting to prevent articles exposed upon the surface of the cover plate 16 60 from falling off.

Formed through the center of the platform 10 is a rectangular opening in which mounted, on hinges 19, two symmetrical plates 20 adapted to be raised nearly vertical, while pivoted on the pin 23 is a seat 24, the same resting, when in a lowered position, upon cross strips 25 which pass from one corner post to another, forming a rigid 70 structure.

In order to hold the cover plate set in the platform and also the seat 24, when in a raised position, there are attached to the inner sides of the adjacent corner posts 15 by screws or like securing means 27, outwardly turned, flat springs 28 having re-entrantly bent ends 29, terminating in beadings 30, the same being adapted to engage in corresponding pockets 32, formed in plates 33, secured by screws or like fastenings 34, 80 to the adjacent edges of the seat and plate 20, so that when the same are raised so as to bring the pockets into engagement with the outwardly sprung pressed beadings 30, holding these elements in a raised position. 85

In operation, a child may rest upon the seat 24 so that the head and shoulders extend through the opening 18, and the apparatus moved over a level surface in an obvious manner. If it be desired that the 90 child walk, the seat 24 is turned upwardly and also the platform plates 20 upon their hinges, permitting the infant to extend its feet through the opening normally covered by the plates 20, and being partially supported by grasping the sides of the structure is readily taught to walk.

Having thus described my invention, and set forth the manner of its construction, application and use, what I claim as new 100 and desire to secure by Letters Patent, is:

In combination with the posts of a plat-

form baby walker having a seat and two symmetrical plates hinged to said platform, cross strips passing from one of said posts to another for supporting said seat in its operative position, outwardly turned flat springs attached to the inner side of adjacent posts, reentrantly bent ends on said springs, a beading, plates provided with

pockets secured to the adjacent edges of said seat and one of said first named plates, said beading adapted to engage in the pockets of said plates, substantially as described and for the purpose set forth.

In testimony whereof I have affixed my signature.

STEFAN ZOCH.
